(57) **CLAIM**

The ornamental design for an inlet filter wrench, as shown and described.

DESCRIPTION

FIG. 1 is a front perspective view of a new design for an inlet filter wrench.

FIG. 2 is a rear perspective view of a new design for an inlet filter wrench.

FIG. 3 is a bottom perspective view of a new design for an inlet filter wrench.

FIG. 4 is a front view of a new design for an inlet filter wrench.

FIG. 5 is a rear view of a new design for an inlet filter wrench.

FIG. 6 is a right side view of a new design for an inlet filter wrench.

FIG. 7 is a left side view of a new design for an inlet filter wrench.

FIG. 8 is a top view of a new design for an inlet filter wrench; and,

FIG. 9 is a bottom view of a new design for an inlet filter wrench.

The broken lines represent portions of the inlet filter wrench that form no part of the claimed design.

1 Claim, 6 Drawing Sheets
